H. HERTZBERG & A. A. LOW.
FUEL HEATER FOR EXPLOSIVE ENGINES.
APPLICATION FILED OCT. 10, 1907.

904,203.

Patented Nov. 17, 1993

UNITED STATES PATENT OFFICE.

HARRY HERTZBERG, OF NEW YORK, AND ABBOT A. LOW, OF HORSESHOE, NEW YORK; SAID HERTZBERG ASSIGNOR TO SAID LOW.

FUEL-HEATER FOR EXPLOSIVE-ENGINES.

No. 904,203.

Specification of Letters Patent.

Patented Nov. 17, 1908.

Application filed October 10, 1907. Serial No. 396,752.

To all whom it may concern:

Be it known that we, HARRY HERTZBERG and ABBOT A. Low, citizens of the United States, residing in the city of New York, borough of Brooklyn, county of Kings, and State of New York, and Horseshoe, county of St. Lawrence, and State of New York, respectively, have invented a certain new and useful Fuel-Heater for Explosive-Engines, of which the following is a specification.

This invention is an explosive engine wherein provision is made for heating the fuel preliminary to vaporizing the same, whereby the efficiency of the engine is increased.

The invention comprises a heating member forming a part of the fuel conduit leading to a vaporizer, such heating member being composed of electrical resistance material, and means for supplying a current of electric energy to said heating member, whereby the member is heated by a current flowing through it, for the purpose of raising the temperature of the liquid fuel or combustible prior to supplying the latter to a vaporizer or carburetor.

In the accompanying drawings, we have illustrated one practical embodiment of the invention, but the construction shown therein is to be understood as illustrative, only, and not as defining the limits of the invention.

Figure 1 is a side elevation of a fuel heater adapted for use in connection with a vaporizer adapted to be connected to an explosive engine. Fig. 2 is a vertical longitudinal section on an enlarged scale through the new fuel heater. Fig. 3 is a cross section showing a metallic insulated lining within the heated resistance hollow member.

The fuel heater of this invention is provided with a hollow member, A, which is composed of an electrical resistance material, such as graphite, carbon or the like. Said hollow member is in the form of a tube, the wall of which is comparatively thick. Said hollow member is provided with means whereby a current of electric energy is caused to flow through the member, and at its respective end portions said member is united by appropriate couplings, B, C, to a vaporizer, D, and a fuel supply pipe, E, respectively.

Each coupling is shown as consisting of

members, b, c, which are separably connected by screws, c', or their equivalents. Between the members, b, c, of each coupling there is interposed a layer of electric insulating material, d, and the screws c', are insulated electrically by bushings, d', whereby the members, b, c, of each coupling are insulated electrically from each other. The members, c, c, of the respective couplings, B, C, are provided with nipples, a, adapted to receive the end portions of the hollow resistance member, A, and said end portions of the hollow member are joined with the members, c, by liquid tight connections indicated at e in Fig. 2.

The members, c, of the couplings B, C, are shown as having the binding posts, f, f', to which are attached suitable wires or conductors forming parts of an electric circuit, whereby an electric current may be caused to traverse the hollow resistance member, A. The binding posts, f, f', are in metallic contact with the members, c, of the couplings, and the carbon resistance member, A, is in good electrical contact with said members, c, of the couplings, thus insuring the passage of electric current through the resistance member, A.

The member, b, of the coupling, B, is shown as having a jet nozzle, g, which is attached to a nipple, h, of an elbow, H, whereby the heater, A, is united by the coupling, B, to said elbow, H. The fuel pipe, E, extends from a suitable oil pump to the coupling, C, and one end of said pipe is united to the member, b, of said coupling, C. The coupling, C, is provided with a fuel passage, i, which is in alignment with the passage, a', of the hollow resistance member, A. The other coupling, B, is provided with a fuel passage, i, which extends through the two members, b, c, of said coupling, B, whereby the fuel is adapted to pass through a continuous passage from the fuel pipe, E, to the nozzle, g.

In the drawings, we have shown the fuel heating member as arranged in a substantially horizontal position, and as being located between the elbow, H, and the fuel supply pipe, E, but this position of the fuel heater and its relation to the other parts are not essential features of the invention. We may arrange the fuel heater, A, in an upright position or in an inclined position, as will be evident to those skilled in the art.

In Fig. 2, the hollow member, A, is shown as having a longitudinal passage, a' , which is of greater diameter than the passage, i , i' , in the couplings, and is, also, of greater diameter than the pipe, E, whereby the hollow member, A, is adapted to contain a quantity of fuel for the purpose of heating said fuel before it is forced into the vaporizer. The hollow resistance member, A, is provided with an external jacket of heat retaining material, said jacket being shown in Fig. 2 as composed of strands or cords of asbestos, I. The asbestos cord is wound two or more times on the hollow member, A, so as to produce a coiled jacket which extends between the members, c , of the couplings, B, C. The jacket incases the hollow member, A, for substantially its length, and, if desired, an additional layer, i'' , of asbestos may be wound on the coiled superimposed layers, I. The jacket may be composed of other heat confining material than the asbestos, it being preferred to employ a material which will confine the heat in the hollow member, A.

In Fig. 1, the novel form of fuel heater is shown in connection with an elbow, H, and a vaporizer or carbureter, D. The elbow, H, forms a guide for a stem, j , of a reciprocating intake valve, J, which normally closes a port, j , in the head, J', of the cylinder forming a part of an internal combustion engine. The vaporizer is coupled to the elbow, H, and it is shown as having an air inlet, k, the area of which is regulated by the adjustment of a suitable valve or damper, K. Within the chamber of the vaporizer, D, is an electrically heated member, L, the latter being in the path of a spray adapted to be supplied to the vaporizer, D, by the jet nozzle, g. The vaporizing member, L, is of the type disclosed in prior applications filed by the parties hereto, and it is not considered necessary to particularly describe the construction and mode of operation of said vaporizing member, L. The stem, j , of the intake valve, J, is impelled in one direction by a spring, m, the tension of which keeps the valve, J, normally closed on its seat, but the valve is adapted to be opened by the operation of a suitable mechanism, herein shown as a lever, O, adapted to engage with the stem, j , said lever being operated by a rod, o, the latter being reciprocated by or from a moving part of the engine.

The operation of the invention will be readily understood from the foregoing description taken in connection with the drawings. A current of electric energy is admitted by one binding post, as f , to the hollow member, A, and flows through said member to the other binding post, as f' , thereby heating said member, A. The member in turn heats the column of liquid fuel which is contained in the member or which passes through said member, and the heat is retained in said member by the non-conducting jacket, I. The fuel pump forces the liquid fuel through the pipe, E, and the member, A, so that the nozzle, g, will spray the fuel into the vaporizer, D, and against the member, L, therein, whereby the liquid fuel is converted into vapor. The operation of the engine opens the valve, J, and the suction produced by the movement of the piston draws in air through the port, k, the air being mixed with the vaporized fuel and producing a combustible charge which is drawn into the engine cylinder, said charge being subsequently compressed or exploded in the usual way.

Although we have shown and described the hollow heating member as having an axial passage a' , through which the liquid fuel is adapted to flow, we do not desire to limit ourselves to this detail, for the reason that we may provide a metallic lining, A', within the graphite or carbon resistance member, A, as shown in Fig. 3. The lining, A', is tubular, and it is arranged within the hollow member, A, so as to be heated thereby. Said lining is insulated from direct contact with the carbon tube or member, A, by an interposed layer of mica, a'' , thus overcoming a short circuit. The lining is composed, preferably, of copper, and it is heated by the resistance member, A, whereby the liquid fuel flowing through the lining is adapted to be heated.

Having thus fully described the invention, what we claim as new, and desire to secure by Letters Patent is:

1. In a device of the class described, a vaporizer, a hollow heating member positioned externally on said vaporizer and forming a part of a conduit for supplying a liquid combustible or fuel to said vaporizer, said heating member being composed of electrical resistance material, and means for supplying an electric current to said heating member.
2. In a device of the class described, a vaporizer, a hollow heating member composed of carbon, said member forming part of a fuel conduit for supplying a liquid combustible to said vaporizer, and means whereby an electric current may flow through said heating member, whereby liquid fuel may be heated preliminary to converting the same into a vapor within said vaporizer.
3. In a device of the class described, a vaporizer, a fuel pipe, a hollow heating member composed of electrical resistance material, means for coupling said heating member to the fuel pipe and the vaporizer, and means for supplying an electric current to the heating member.
4. In a device of the class described, a vaporizer, a fuel pipe, a hollow heating member composed of electrical resistance material, means for coupling said heating

member to the fuel pipe and the vaporizer, means for electrically insulating the heating member from the fuel pipe and the vaporizer, and means whereby an electric current is caused to flow through said heating member.

5. In a device of the class described, a vaporizer, a fuel pipe, a hollow fuel-heating member composed of electrical resistance material and forming a part of said pipe, a coupling intermediate the vaporizer and said hollow member, said coupling being electrically insulated and being provided with a fuel passage, and means for electrically heating said hollow member.

6. In a device of the class described, a vaporizer, a fuel pipe, a hollow fuel-heating member composed of electrical resistance material and forming a continuation of said fuel pipe, a coupling intermediate the fuel pipe and the hollow member, said coupling being provided with a fuel passage and being insulated electrically, and means for heating said hollow member.

5. 7. In a device of the class described, a vaporizer, a fuel pipe, a hollow member composed of electrical resistance material, means for electrically heating said hollow member, and couplings uniting the hollow member with the fuel pipe and the vaporizer, said couplings having means for electrically insulating said hollow member from the vaporizer and the fuel pipe.

8. In a device of the class described, a vaporizer, a hollow fuel-heating member composed of electrical resistance material, said hollow member being positioned externally on said vaporizer and in communication therewith, means whereby said hollow member may be included in an electric circuit, and a heat-insulating jacket incasing said hollow member.

9. In a device of the class described, a vaporizer, a hollow fuel-heating member composed of electrical resistance material, said hollow member being coupled externally to said vaporizer and communicating

therewith, means whereby said hollow member may be included in an electric circuit, and separable couplings at the respective end portions of said hollow member.

10. In a device of the class described, a vaporizer, a hollow fuel-heating member composed of electrical resistance material, means whereby said hollow member may be included in an electric circuit, and separable couplings at the respective end portions of said hollow member, each coupling being provided with an electrical insulation between the separable portions thereof, one of said couplings uniting said hollow member to the vaporizer.

11. In a device of the class described, a vaporizer, a hollow fuel-heating member composed of electrical resistance material, means whereby said hollow member may be included in an electric circuit, a fuel pipe, couplings at the respective end portions of the hollow member, for uniting the latter to the vaporizer and the fuel pipe, and a non-conducting jacket incasing the hollow member.

12. In a device of the class described, a vaporizer, a hollow fuel-heating member composed of electrical resistance material, means whereby said hollow member may be included in an electric circuit, a fuel pipe, separable metallic couplings at the respective end portions of the hollow member for uniting the hollow member to said vaporizer and the fuel pipe, each coupling having an electrical insulation between the separable parts thereof, and a non-conducting jacket incasing the hollow member and extending between the couplings thereon.

In testimony whereof we have signed our names to this specification in the presence of two subscribing witnesses.

HARRY HERTZBERG.
